CLAIM

The ornamental design for a confectionery bar, as shown and described.

DESCRIPTION

FIG. 1 is a top, left perspective view of a first embodiment of a confectionery bar;
 FIG. 2 is a right side elevational view of the confectionery bar of FIG. 1;
 FIG. 3 is a left side elevational view of the confectionery bar of FIG. 1;
 FIG. 4 is a front elevational view of the confectionery bar of FIG. 1;
 FIG. 5 is a rear elevational view of the confectionery bar of FIG. 1;
 FIG. 6 is a top plan view of the confectionery bar of FIG. 1;
 FIG. 7 is a bottom plan view of the confectionery bar of FIG. 1;
 FIG. 8 is a top, left perspective view of a second embodiment of a confectionery bar;
 FIG. 9 is a right side elevational view of the confectionery bar of FIG. 8;
 FIG. 10 is a left side elevational view of the confectionery bar of FIG. 8;

FIG. 11 is a front elevational view of the confectionery bar of FIG. 8;

FIG. 12 is a rear elevational view of the confectionery bar of FIG. 8;

FIG. 13 is a top plan view of the confectionery bar of FIG. 8;

FIG. 14 is a bottom plan view of the confectionery bar of FIG. 8;

FIG. 15 is a top, left perspective view of a third embodiment of a confectionery bar;

FIG. 16 is a right side elevational view of the confectionery bar of FIG. 15;

FIG. 17 is a left side elevational view of the confectionery bar of FIG. 15;

FIG. 18 is a front elevational view of the confectionery bar of FIG. 15;

FIG. 19 is a rear elevational view of the confectionery bar of FIG. 15;

FIG. 20 is a top plan view of the confectionery bar of FIG. 15;

FIG. 21 is a bottom plan view of the confectionery bar of FIG. 15;

FIG. 22 is a top, left perspective view of a fourth embodiment of a confectionery bar;

FIG. 23 is a right side elevational view of the confectionery bar of FIG. 22;

FIG. 24 is a left side elevational view of the confectionery bar of FIG. 22;

FIG. 25 is a front elevational view of the confectionery bar of FIG. 22;

FIG. 26 is a rear elevational view of the confectionery bar of FIG. 22;

FIG. 27 is a top plan view of the confectionery bar of FIG. 22;

FIG. 28 is a bottom plan view of the confectionery bar of FIG. 22;

FIG. 29 is a top, left perspective view of a fifth embodiment of a confectionery bar;

FIG. 30 is a right side elevational view of the confectionery bar of FIG. 29;

FIG. 31 is a left side elevational view of the confectionery bar of FIG. 29;

FIG. 32 is a front elevational view of the confectionery bar of FIG. 29;

FIG. 33 is a rear elevational view of the confectionery bar of FIG. 29;

FIG. 34 is a top plan view of the confectionery bar of FIG. 29;

FIG. 35 is a bottom plan view of the confectionery bar segment of FIG. 29;

FIG. 36 is a top, left perspective view of a sixth embodiment of a confectionery bar;

FIG. 37 is a right side elevational view of the confectionery bar of FIG. 36;

FIG. 38 is a left side elevational view of the confectionery bar of FIG. 36;

FIG. 39 is a front elevational view of the confectionery bar of FIG. 37;

FIG. 40 is a rear elevational view of the confectionery bar of FIG. 37;

FIG. 41 is a top plan view of the confectionery bar of FIG. 37; and,

FIG. 42 is a bottom plan view of the confectionery bar of FIG. 37.

The break lines shown in the middle portion of the confectionery bar in FIGS. 1-3, 6-7, 15-17, 20-21, 29-31 and 34-35 indicate that the appearance of any portion of the article between the break lines forms no part of the claimed design.
